(No Model.)

G. MARTEL.

WATCH MAKER'S STAKING TOOL.

No. 403,849.

Patented May 21 1889.

UNITED STATES PATENT OFFICE.

GASPARD MARTEL, OF BOSTON, MASSACHUSETTS.

WATCH-MAKER'S STAKING-TOOL.

SPECIFICATION forming part of Letters Patent No. 403,849, dated May 21, 1889.

Application filed March 1, 1889. Serial No. 301,650. (No model.)

To all whom it may concern:

Be it known that I, GASPARD MARTEL, a citizen of Canada, and a resident of Boston, in the county of Suffolk and State of Massachusetts, have invented new and useful Improvements in Staking-Tools, of which the following, taken in connection with the accompanying drawings, is a specification.

This invention relates to improvements in staking-tools of the kind used by jewelers for the purpose of staking or securing staffs or pinions to watch-wheels and for other similar purposes, reference being had to the accompanying drawings, wherein—

15 Figure 1 represents a plan view of the improved staking-tool. Fig. 2 represents a central longitudinal section on the line X X, shown in Fig. 1. Fig. 3 represents a cross-section on the line Y Y, also shown in Fig. 1; and Figs. 4 and 5 represent, respectively, in plan and elevation a modification of the invention.

Similar letters refer to similar parts wherever they occur on the different parts of the drawings.

25 The invention relates to improvements in that kind of jewelers' staking-tools in which the perforated bed-plate is stationary, and it is constructed as follows:

30 *a* is the base, to the top of which is secured the bed-plate *b*, which is cylindrical in form and preferably secured to the base *a* by means of a screw, *a'*, and steady-pin, *a''*, as shown in Figs. 2 and 3, or in any other suitable or equivalent manner, it being only essential that the bed-plate shall be firmly secured to the said base.

35 *B* are a series of perforations of varying diameters in the bed-plate *b*, which perforations are arranged equidistant from the axis or center of the said bed-plate, as shown, and centrally below such perforations are made through the base *a* the perforations *A A*, as is common in staking-tools.

40 In one piece with or secured to the base *a* is made the standard or post *c*, the upper end of which terminates as a vertical cylinder or hub, *c'*, having a cylindrical vertical bore or recess adapted to receive the cylindrical pin *d*, the axis of which coincides with the axis 45 of the bed-plate *b*, as shown. On the pin *d*

is pivoted the inner end of the arm or tool-guide *e*, that is adapted to swing on said pin in a horizontal plane. The arm *e* has in its outer free end a vertically-perforated tool-guide, *e'*, adapted to receive the punch or stake *f*, the axis of which coincides with the axis of either one of the bed-plate perforations *B* as the arm *e* is swung around the pivot-pin *d'*.

55 For the purpose of securing the arm *e* to the hub *c'* after it has been adjusted in its proper position relative to any one of the bed-plate perforations, I prefer to use an eccentric pin or binder, *g*, going through horizontal perforations in the hub *c'* and pin *d* and provided with a knob or handle, *g'*, in one end and a set-screw, *g''*, in the other to prevent its getting detached from said hub and pin, as shown.

60 *d'* is a head in the upper end of the pin *d*, as shown. In using the tool the staff, arbor, &c., that is to be staked is fitted in one of the

65 bed-plate perforations, I prefer to use an eccentric pin or binder, *g*, going through horizontal perforations in the hub *c'* and pin *d* and provided with a knob or handle, *g'*, in one end and a set-screw, *g''*, in the other to prevent its getting detached from said hub and pin, as shown.

70 *d* is a head in the upper end of the pin *d*, as shown. In using the tool the staff, arbor, &c., that is to be staked is fitted in one of the

75 bed-plate perforations, I prefer to use an eccentric pin or binder, *g*, going through horizontal perforations in the hub *c'* and pin *d* and provided with a knob or handle, *g'*, in one end and a set-screw, *g''*, in the other to prevent its getting detached from said hub and pin, as shown.

75 *d* is a head in the upper end of the pin *d*, as shown. In using the tool the staff, arbor, &c., that is to be staked is fitted in one of the

80 bed-plate perforations, I prefer to use an eccentric pin or binder, *g*, going through horizontal perforations in the hub *c'* and pin *d* and provided with a knob or handle, *g'*, in one end and a set-screw, *g''*, in the other to prevent its getting detached from said hub and pin, as shown.

85 *d* is a head in the upper end of the pin *d*, as shown. In using the tool the staff, arbor, &c., that is to be staked is fitted in one of the

85 bed-plate perforations, I prefer to use an eccentric pin or binder, *g*, going through horizontal perforations in the hub *c'* and pin *d* and provided with a knob or handle, *g'*, in one end and a set-screw, *g''*, in the other to prevent its getting detached from said hub and pin, as shown.

90 *d* is a head in the upper end of the pin *d*, as shown. In using the tool the staff, arbor, &c., that is to be staked is fitted in one of the

95 bed-plate perforations, I prefer to use an eccentric pin or binder, *g*, going through horizontal perforations in the hub *c'* and pin *d* and provided with a knob or handle, *g'*, in one end and a set-screw, *g''*, in the other to prevent its getting detached from said hub and pin, as shown.

100 In the modification shown in Figs. 4 and 5 I have shown the post or standard *c* secured to the center of the bed-plate *b*, the arm *e* being pivoted to a pin in its upper end in the same manner as hereinabove described, and

by securing such post centrally on the plate *b*, I am enabled to swing the arm *e* a complete revolution around its axis, thus using additional perforations in the bed-plate.

Having thus fully described the nature, construction, and operation of my invention, I wish to secure by Letters Patent, and claim—

The stationary perforated bed-plate *b* and stationary base *a*, having the post or standard *c* and vertical pivot-pin *d*, having its axis coinciding with that of the plate *b*, in combination with the stake or punch carrying arm

e, pivoted on the pin *d*, and a locking device for securing said arm to the standard *c* after being adjusted, substantially in a manner and for the purpose set forth. 15

In testimony whereof I have signed my name to this specification, in the presence of two subscribing witnesses, on this 25th day of February, A. D. 1889.

GASPARD MARTEL.
